ABSTRACT: A reservoir of liquid metal is connected to an ion thruster for a supply of ionizable material thereto. The reservoir is in the form of a reservoir cylinder having a reservoir piston therein. An associated drive cylinder contains a drive piston connected to the reservoir piston. A liquid in equilibrium with its vapor is positioned in the drive cylinder, and as heat is added, the pistons move to deliver liquid metal to the thruster. The amount of heat supplied to the drive cylinder is preferably a function of the liquid-metal requirements of the ion thruster.

LIQUID-METAL FEED SYSTEM FOR FEEDING PROPELLANT TO AN ION THRUSTOR

CROSS REFERENCE

This invention is divided out of patent application Ser. No. 602,664, now U.S. Pat. No. 3,443,383, filed Dec. 19, 1966, entitled "Fluid Feed System."

BACKGROUND

This invention relates primarily to a fluid feed system, and more particularly to methods and apparatus for controllably feeding propellant from a reservoir to an ion engine.

Prior to the present invention, liquid mercury propellant was fed from a mercury reservoir to a mercury ion thruster by using a high pressure gas from a high pressure gas bottle whose pressure was controlled by a mechanical regulator in the feedline between the bottle and the reservoir.

The reservoir was a spherically shaped container with a flexible metal diaphragm separating the mercury and the gas. This was a one-shot system since the reservoir could not be refilled. The diaphragm was supposed to turn itself inside-out as the mercury was used up. However, the diaphragm often ruptured and also unfolded in such a way as to catch quantities of mercury in small pockets so that all of the mercury was not available for use. Flexible elastomeric diaphragms were found to be subject to most of the same disadvantages.

Further, because such regulators possess a small but finite leak rate and because gas must be vented to reduce system pressure, large amounts of gas would be consumed over the long ($>10^4$ hours) required life of an ion thruster feed system. Rough calculation indicates that the high pressure gas bottle required would be larger than the mercury reservoir itself.

SUMMARY

As an aid in the understanding of this invention, it can be stated in essentially summary form that it is directed to a feed system for feeding ionizable material to an ion engine, the feed means comprising a reservoir cylinder having a piston therein, and a drive cylinder having a piston therein. The pistons are connected so that motion on the drive piston causes motion of the reservoir piston. The pressure on the drive piston is controlled by thermally adjusting the vapor pressure of the liquid-vapor above the drive piston to control the flow rate out of the reservoir cylinder to the ion engine. Such control can be in accordance with the requirements of ion engine for ionizable material.

It is therefore, a primary object of the present invention to provide a fluid feed system which is not subject to the above disadvantages inherent in previous feed systems. It is a further object of the invention to provide a fluid feed system which does not require a bulky gas storage bottle or a mechanical regulator. It is another object of the invention to provide a fluid feed system which does not require the venting of gas to reduce pressure on the fluid. It is still a further object of the invention to provide a fluid feed system in which the only moving part is a slow moving piston which rides on low stick bearings. It is another object of the invention to provide a liquid mercury feed system for use which provides smooth, high pressure, mercury feed at low flow rates. It is another object of the invention to provide a propulsion system comprising a liquid mercury cathode and liquid mercury storage and flow control means. It is another object of the invention to provide a fluid feed system in which essentially all of the fluid is available for use.

These and other objects and advantages of the present invention will be more fully understood by reference to the following detailed description when read in conjunction with the attached drawing.

DESCRIPTION OF THE DRAWING

The single FIGURE of the drawing is a partly schematic longitudinal section through the ionizable fluid feed system of this invention.

Referring to the drawing, the FIGURE shows a liquid mercury reservoir 2 adapted to contain a quantity of mercury in a chamber 4 therein. In the preferred embodiment, the mercury in chamber 4 is fed under pressure through a conduit 5 to a thruster 7 (such as a Kaufman engine such as is shown in Pat. No. 3,156,090). Other elements of such a system such as valves, a vaporizer and an isolator, are conventional and form no part of this invention and need not be described in detail herein. However, in the embodiment described herein, the control for the propellant feed includes a closed loop in which changes in the ion beam, as signalled by the beam current I_B , provide the control signal to vary the propellant feed rate. It is noted that this system is applicable to other liquids than mercury and also to fluids and for other applications than for feeding propellant to ion engines.

Attached to the reservoir 2 is a pressurizer section 6 which contains a piston and cylinder arrangement comprising a stationary cylinder 10 inside of which is mounted a piston 8 comprising a piston head 9 attached to a bellows 11. A liquid is contained in the chamber 12 between the piston 8 and the cylinder 10. In the preferred embodiment, this liquid is water in equilibrium with its saturated vapor. The vapor pressure of the liquid is a unique function of the temperature of the cylinder 10. The temperature of the liquid in the chamber 12 is controlled by means of a heater 14, which comprises a heater filament helically wound upon and in contact with the outer surface of the cylinder 10. As the volume of the cylinder 12 increases due to motion of the piston 8, the liquid in the chamber 12 evaporates so as to maintain the saturated vapor condition.

The pressurizer 6 and the reservoir 2 are thermally isolated from each other and the force from the pressure of vapor in the chamber 12 is transmitted from the pressurizer 6 to the reservoir 2 through a push rod 16 of low thermal conductivity material. A stainless steel shield 13 aids in insulating the pressurizer 6 from the reservoir 2. Thermal isolation is desired so that the temperature of the relatively low mass of the pressurizer may be rapidly changed by small amounts of input power. With tight thermal coupling between the pressurizer 6 and the reservoir 2, it would be necessary to change the temperature of both the pressurizer 6 and the mercury reservoir 2, which could contain several hundred pounds of mercury. In such a case, this system would have intolerably slow response.

The mercury in the chamber 4 is contained by means of a seal 18 between the side of the reservoir 2 and a piston 20. The side of the reservoir 2 and the piston 20 may be considered another piston-cylinder configuration similar to the piston-cylinder configuration in the pressurizer 6. The seal 18 is preferably of the "rolling diaphragm" type to reduce friction and contamination. If an all-metal system was required for high temperature or high pressure operation, the seal 18 can equally well be made with a metal bellows which allows a long stroke. The piston 20 provided with a cylindrical skirt 22 to prevent the diaphragm 18 from bulging as the mercury is expelled and to insure that all of the mercury is available for use in the system.

In actual operation, the embodiment shown has been used to supply liquid mercury flow rates from 0 to 1 cc./hr. to a liquid-mercury cathode while it was operating in an ion thruster and to supply liquid mercury at constant pressure (about 7 p.s.i.) to a vaporizer operating as part of a vapor feed system for an ion thruster using an oxide cathode. Closed loop operation using the ion beam current as the input signal has been demonstrated to be useful with a liquid-mercury thruster. This closed loop operation is schematically shown in the drawing.

The drawing shows ion thruster 7 connected to the chamber 4 by means of the conduit 5. The thruster 7 can be any of the known types of ion thrusters, such as the Kaufman engine, and can employ, for example, a liquid-mercury cathode or a thermionic cathode.

A control circuit is illustrated for use with a liquid-metal cathode, for which it is desirous to vary the pressure on the mercury in the reservoir in order to vary the flow of propellant

to the thruster. The ion beam current I_B is passed through a fixed resistor 26 to develop a voltage. This voltage is compared to a reference voltage 27 by means of a differential amplifier 28. The resulting difference signal is amplified by a power amplifier 29 such as a magnetic amplifier and a silicon controlled rectifier. The amplified difference signal is used by a power controller 30 to adjust and control the power going to the heater 14 of the pressurizer 6. This control loop controls the temperature of the pressurizer, hence the driving pressure, and ultimately the mercury flow rate and the ion beam current. In other applications of this invention, the control signal to the power controller 30 can originate from a fluid flow measuring device positioned in the outlet conduit 5.

This invention having been described in its preferred embodiment, it is clear that it is susceptible to numerous modifications and embodiments within the ability of those skilled in the art and without the exercise of the inventive faculty. Accordingly, the scope of this invention is defined by the scope of the following claims.

I claim:

1. Apparatus for controllably feeding a fluid material comprising:
 an enclosed reservoir adapted to contain a quantity of fluid material, said enclosed reservoir comprising a first piston 25
 slidably mounted in a first cylinder so that movement of
 said first piston expels fluid material from said first cylinder;
 means for receiving the fluid material;
 conduit means connected between said reservoir and said receiving means for providing fluid communication 30
 therebetween;
 a pressurizer having an enclosed pressurizer chamber
 adapted to contain a quantity of liquid in equilibrium with
 its vapor, means for maintaining said pressurizer in ther-

mal isolation;
 said pressurizer comprising a second cylinder closed at one end and provided with a second movable piston slideably mounted in said second cylinder in sealing engagement with the walls thereof to define a pressurizing chamber therein adapted to contain a quantity of liquid in equilibrium with its vapor, said first piston being connected to be moved by said second piston;
 heater means associated with said second cylinder for heating the liquid in said pressurizing chamber for controlling the temperature of the liquid and vapor in said chamber;
 and
 means responsive to the rate of flow of said fluid material from said reservoir for controllably energizing said heater means.
 2. Apparatus for controlling the flow of liquid mercury from a reservoir to an ion thruster comprising:
 a reservoir adapted to contain a quantity of mercury;
 a piston slideably mounted in said reservoir for varying the volume thereof;
 a rolling diaphragm sealing means for sealing said piston in said reservoir;
 an ion thruster;
 conductor means connected between said reservoir and said thruster for providing fluid communication therebetween;
 a pressurizer comprising a piston-cylinder arrangement defining a pressurizing chamber adapted to contain a quantity of liquid in equilibrium with its vapor;
 heater means associated with said pressurizer; and
 means responsive to the rate of flow of mercury from said reservoir for energizing said heater means.
